UNITED STATES PATENT OFFICE

THOMAS E. MURRAY, JR., AND IRVING T. BENNETT, OF BROOKLYN, NEW YORK, ASSIGNEES, BY DIRECT AND MESNE ASSIGNMENTS, TO MURRAY RADIATOR CORPORATION, A CORPORATION OF NEW YORK

RADIATOR

Application filed February 15, 1927. Serial No. 168,272.

In a certain previous Murray application No. 709,080, filed April 26, 1924 there is described a type of radiator with a steam pipe or similar heating element to the back and front of which are applied transverse plates forming an extended radiating surface which conducts the heat rapidly to the surrounding air and circulates the heated air rapidly; and this principle is embodied in several other pending Murray applications.

The present invention aims to provide certain improvements adapted to this and similar types of radiator.

Fig. 1 is a perspective view of the complete radiator;

Fig. 2 is a front elevation of one end thereof;

Fig. 3 is a horizontal section on the line 3—3 of Fig. 2;

Fig. 4 is a vertical section on the line 4—4 of Fig. 2;

Fig. 5 is a similar section at an intermediate stage of production;

Figs. 6, 7 and 8 are similar sections of modifications.

Fig. 9 is a view similar to Fig. 7 of the parts before welding.

Fig. 10 is an elevation, partly in section of the electric heating element.

In Figs. 1 to 7 the heating element is a pipe arranged in three approximately horizontal lengths 1, 2 and 3 connected by bends at alternate ends, so that the steam or other heating medium flows through it continuously.

Or they may be arranged in a parallel with headers at opposite ends. One or more pipe lengths or other heating elements may be used.

The radiating structure comprises metal sheets corrugated in horizontal section and forming short longitudinal portions 4 and 6 connected by transverse plates or fins 5. The inner longitudinal portions 4 engage the pipe 1 at the front and back and conduct the heat therefrom to the plates 5 which transmit it to the surrounding air and form vertical flues or chimneys to induce a rapid circulation. The rapid conduction of the heat through the close contact with the pipe and the rapid radiation through the extended fins, together

with the rapid circulation of air induced, adapt the radiator for use with high temperature steam or electricity or other heating medium.

The heating element and the radiating structure may be of various metals. We prefer to make the pipe of copper or an alloy thereof to assist in the rapid operation described, although a ferrous metal may be used. In a particular instance we have made it of tinned copper tubing. We prefer to make the radiating structure, for economy, of steel (in which term we include iron and alloys thereof).

Where copper and steel, or other metals having different coefficients of expansion, are used the radiating structure cannot be secured to the heating element by soldered or similar bonded unions. Such joints would be loosened by the unequal expansion in a short time. We propose therefore to secure the radiating structure movably but in close contact with the outside of the heating element, so as to obtain high thermal conductivity through the joint so that the fin temperatures may be approximately those of the heating element. The copper tubes with or without the strips 7 and 8, closely embraced in recesses in the outside structure of steel or iron, has this further advantage. When the temperature is raised the expansion of the parts within the steel pieces is greater than that of the steel itself because of the lower co-efficient of thermal expansion of the latter. Therefore, the contact between all the parts is made more intimate by the resulting pressure and there is a better transmission of heat. There will be some expansion of the embracing parts of steel; but this will generally be within the elastic limit of the steel so that when the parts are cooled they will be restored to their original dimensions.

This may be done in various ways. In Fig. 4 the plates 4 are provided with recesses 6 embracing the pipe 1. The plates are spaced slightly apart with bars or strips 7, 8, between them and are fastened together by welds 9 and 10 immediately above and below the pipe. These are referred to as

"spot" welds, but they may be larger or smaller in area according to requirements, or may be of the type known as projection welds. The parts are first assembled in the position of Fig. 5. The welding tools then force the plates 4 into close embrace of the pipe in the manner shown in Fig. 4 and weld them firmly together. Such joints by welding two pieces through an intermediate piece are illustrated more fully, and are claimed for other structures than radiators, in our application No. 203,437 filed July 5, 1927; and the method, in our application No. 203,438 filed July 5, 1927.

The plates 4 may be brought together without the interposition of a filler, as in Fig. 6 and fastened as before in close embrace of the pipe by spot welds 9 and 10. Where fillers 7 are used they may extend continuously lengthwise as in the case illustrated in Fig. 1 for the fillers 7, or they may be short pieces, one at each joint.

In some locations it is desirable to have the radiating structure at one side only of the heating element. Fig. 7 illustrates this. The radiating structure is shaped as in Fig. 6. It is secured on one or more pipes 1 by straps 11 passing around the opposite side of the pipes and slightly above and below the same and fastened to the plates 6 by welds 9 and 10. A single strap 11 may be used extending lengthwise of each pipe section. Or short separate straps may be used, one for each joint.

Instead of the steam pipes in the above figures, electric heating elements (of the usual resistance or other type) may be used. Fig. 8 shows this in a construction similar to Fig. 7, using one or more heating elements like that indicated at 12. They are held against the plates 4 by means of straps 13 similar to the straps 11 of Fig. 7 and fastened to the plate 4 by similar spot welds 9 and 10. There are certain advantages in providing for heating the radiator by both steam and electricity. This can be accomplished with our invention by adding one or more electric elements to the radiator of Fig. 2 or by replacing one or more of the pipe lengths in this figure with electric heating elements.

In order to secure the desired close contact of the radiating structure to the heating element, the plate 4 (or the plates 4 at opposite sides, where a two-sided radiator is to be built) are first bent as in Fig. 9 with portions 14 tangent to the tube 1. Then in the welding machine, these are pressed together to the shape of Fig. 7 at the same time that the welding current is passed. This operation stretches the metal tightly over the heating element.

In Fig. 10, we have indicated the preferred style of electric heating element. This is of the type described fully in a patent of

Wiegand, January 18, 1927, No. 1,614,938. A corrugated strip 15 is encased in non-conducting material 16 in a long thin shell 17 of steel, with binding posts 18 at the ends projecting outside of the shell. Such strip heaters become very hot in use, red hot in fact, and are dangerous when exposed to contact. But when embraced in the extended area of the radiating structure herein described, the heat is taken away from them so fast that they keep moderately cool and the resulting structure is quite safe as far as the risk of fire or injury to persons is concerned, and the life of the heater is prolonged.

The radiator may be equally used for cooling air by circulating cold brine or the like through the pipes so that the latter become a heating element only in the negative sense, that is, they extract heat from the radiating structure and induce a flow of the cool air downward through the flues similar to the upward circulation of air induced by the passage of steam through the pipes.

Various other modifications may be made by those skilled in the art without departing from the invention as defined in the following claims.

What we claim is:

1. A radiator including in combination a heating element and a radiating structure having a different coefficient of expansion extending continuously lengthwise of the heating element and in contact with it at separated points and movably secured to it at such points.

2. A radiator including in combination a heating element of copper and a radiating structure of steel extending continuously lengthwise of the heating element and movably secured at separated points in contact with the outside of said element.

3. A radiator including in combination a heating element and a radiating structure having a different coefficient of expansion extending continuously lengthwise of the heating element and formed of parts which embrace said element at separated points in its length and are secured to each other at points beyond the heating element.

4. A radiator including in combination a heating element of copper and a radiating structure of steel and formed of parts which embrace said element and are welded to each other at points beyond the heating element.

5. A radiator including in combination a heating element of copper and a radiating structure of steel formed of parts located on opposite sides of said element and fastened to each other at points outside of and closely adjacent to the heating element.

6. A radiator including in combination a heating element of copper and a radiating structure of steel comprising longitudinal portions and transverse portions, the longitudinal portions located on opposite sides of

said element and being fastened to each other at points outside of and closely adjacent to the heating element.

7. A radiator including in combination a heating element of copper in a substantially horizontal position and a radiating structure of steel having vertically extending portions engaging the front and back of the heating element and fastened together at points immediately above and below the heating element.

8. A radiator including in combination a horizontally extending heating element and a radiating structure having a different coefficient of expansion and consisting of a single plate extending integrally the length of the heating element, corrugated in horizontal section to form vertical flues and movably secured to the heating element to permit expansion of one part relative to the other.

9. A radiator including in combination a heating element of non-ferrous material and a radiating structure of ferrous material secured about the heating element so as to provide a joint of high thermal efficiency and yet to allow enough freedom of movement to take care of the unequal expansions of the two over the contacting length.

30 10. A radiator including in combination a horizontally extending heating element and a radiating structure having a different coefficient of expansion and including a plate extending integrally lengthwise of the heating element, corrugated in horizontal section to form vertical flues and movably secured to the heating element to permit expansion of one part relatively to the other.

40 11. A radiator including in combination a copper tube and a radiating structure including a steel plate extending lengthwise of the tube, corrugated in horizontal section to form vertical flues and movably secured to the tube at separated points along the length of the latter to permit expansion of one part relatively to the other.

50 12. A radiator for heating the air of a room including in combination a heating element and a radiating structure comprising plates embracing the heating element at separated points in its length with their faces brought together at points beyond it and welded to each other, said plates having vertically extending passages between them in which the air is heated and through which an ascending current of heated air is induced.

60 13. A radiator for heating the air of a room including in combination a heating element and a radiating structure comprising a sheet corrugated in horizontal section and extending lengthwise of the heating element with the inner portions of the corrugations engaging the heating element and fastened by welding to each other and to the heating ele-

ment, said sheet forming vertically extending passages in which the air is heated and through which an ascending current of heated air is induced.

14. A radiator for heating the air of a room including in combination a heating element and a radiating structure comprising horizontally corrugated sheets extending lengthwise of the heating element with the inner portions of corrugations embracing it on opposite sides and welded to each other, said sheets forming vertically extending passages in which the air is heated and through which an ascending current of heated air is induced.

In witness whereof, we have hereunto signed our names.
